UNITED STATES PATENT OFFICE.

GILES A. BECKWITH, OF WATERFORD, AND CHARLES L. LAMPHERE, OF NORWICH, CONNECTICUT.

SASH-WEIGHT.

SPECIFICATION forming part of Letters Patent No. 707,197, dated August 19, 1902.

Application filed October 22, 1901. Serial No. 79,530. (No model.)

To all whom it may concern:

Be it known that we, GILES A. BECKWITH, residing at Waterford, and CHARLES L. LAMPHERE, residing at Norwich, Connecticut, 5 citizens of the United States, have invented certain new and useful Improvements in Sash-Weights, of which the following is a full, clear, and exact description.

This invention relates to certain new and 10 useful improvements in sash-weights, and the novelty resides in the peculiar construction pointed out in the appended claim.

The invention is clearly illustrated in the 15 accompanying drawing, which shows a perspective view of a weight constructed in accordance with our invention.

As seen in the drawing, the weight is of hook shape at one end, as denoted by the letter e^2 , which said hook is slotted, as at e^3 . A 20 special pulley h is provided for use with the said weight, said pulley being provided with oppositely-extending axial projections h' . In assembling the weight and pulley the axial

portions h' thereof are received in the hook e^2 , while the pulley proper lies in the slot e^3 , 25 as will be readily understood from the drawing. The pulley h when thus in position in the loop is retained therein by the depending weight e' .

Having thus described our invention, we 30 claim—

A sash-weight having one end hooked and slotted vertically at its upper end and having also side slots, and a pulley having oppositely-extending axial projections engaging in the 35 said side slots, the pulley-body being disposed in the slot at the end of the hook all substantially as shown and described.

Signed at Norwich, Connecticut, this 12th day of October, 1901.

GILES A. BECKWITH.
CHARLES L. LAMPHERE.
